United States Patent Office

Des. 201,982
Patented Aug. 17, 1965

201,982

CLOCK

Raleigh J. Frederickson, 3114 S. Norton,
Sioux Falls, S. Dak.

Filed Aug. 3, 1964, Ser. No. 81,138

Term of patent 14 years

(Cl. D42—7)

FIGURE 1 is a front elevational view of a clock, showing my new design.

FIGURE 2 is a side elevational view thereof; and
FIGURE 3 is a top plan view thereof.

I claim:

The ornamental design for a clock, as shown.
